[57] CLAIM

The ornamental design for mouthpiece for use as a geriatric pacifier or for the treatment of bruxism, as shown and described.

DESCRIPTION

FIG. 1 is a perspective view of a mouthpiece for use as a geriatric pacifier or for the treatment of bruxism showing our new design;

FIG. 2 is a bottom plan view thereof;

FIG. 3 is a top plan view thereof;

FIG. 4 is a front elevational view thereof;

FIG. 5 is a vertical cross-sectional view thereof, taken along line 5—5 of FIG. 3; and

FIG. 6 is a rear elevational view thereof.

The cord element is shown broken-away in FIGS. 2-6 for convenience of illustration.
